FIG. 1.

FIG. 2.

Carl W. Miller ^{INVENTOR}
Chas. Williamson ^{BY}
ATTORNEY

UNITED STATES PATENT OFFICE

CARL W. MILLER, OF UPPER DARBY, PENNSYLVANIA, ASSIGNOR TO JACK RUSKIN, OF PHILADELPHIA, PENNSYLVANIA

DESIGN FOR A BOTTLE

Application filed June 13, 1932. Serial No. 44,067. Term of patent 3½ years.

To all whom it may concern:

Be it known that I, CARL W. MILLER, a resident of Upper Darby, county of Delaware, State of Pennsylvania, and a citizen of the United States, have invented a new, original, and ornamental Design for Bottles, of which the following is a specification, reference being had to the accompanying drawing, forming a part thereof.

In the drawing:

Figs. 1 and 2 are, respectively, side elevations of a bottle showing my new design, the two views being of sides that are ninety degrees apart.

My design is embodied or present in a bottle having a substantially cylindrical body portion and an upwardly tapering neck, the sub-

stantially cylindrical body portion having three zones or bands of substantially equal vertical extent, the lower-most zone being crossed by parallel sinuous or undulating fine ribs, the band next above being plain with the exception of circular concave depressions spaced apart circumferentially, and the third or upper-most band being plain with elliptical panels defined by a fine ridge; and the neck portion of the bottle is crossed by sinuous or undulating parallel fine ridges.

I claim:

The ornamental design for a bottle as shown and described.

In testimony whereof I hereunto affix my signature.

CARL W. MILLER.
